UNITED STATES PATENT OFFICE.

WILLIAM H. NORTON, OF NEW YORK, N. Y.

DESIGN FOR WALL-PAPER OR SIMILAR ARTICLE OF MANUFACTURE.

51,421.

Specification for Design.

Patented Oct. 23, 1917.

Application filed July 3, 1915. Serial No. 37,975. Term of patent 14 years.

To all whom it may concern:

Be it known that I, WILLIAM H. NORTON, a citizen of the United States, residing at Bedford Park, in the county of Bronx, city of New York, State of New York, have invented a new, original, and ornamental Design for Wall-Paper or Similar Article of Manufacture, of which the following is a specification, reference being had to the accompanying drawing, forming a part hereof.

The figure is a plan view of a sheet of wall paper embodying my design.

Copies of this patent may be obtained for five cents each, by addressing the "Commissioner of Patents, Washington, D. C."

It is also contemplated to use the design for textile fabrics or other material of sheet form.

I claim—

The ornamental design for wall paper or similar article as shown.

WILLIAM H. NORTON.
